[57] **CLAIM**

The ornamental design for a vehicular pipe, as shown and described.

DESCRIPTION

FIG. 1 is perspective view of a vehicular pipe, showing my new design;

FIG. 2 is a top plan view thereof;

FIG. 3 is a left elevational view thereof;

FIG. 4 is a right elevational view thereof;

FIG. 5 is a bottom elevational view thereof;

FIG. 6 is a right elevational view thereof, showing the device on one possible environment, the broken-line showing of environmental structure is for illustrative purposes only and forms no part of the claimed design; and,

FIG. 7 is an enlarged front view thereof, wherein the rear view is a mirror image thereof.
